UNITED STATES PATENT OFFICE.

CHARLES C. HEBBARD, OF JOPLIN, MISSOURI, ASSIGNOR OF ONE-THIRD TO EDWARD H. SHACKELFORD AND ONE-THIRD TO OTTO RUHL, BOTH OF JOPLIN, MISSOURI.

CONCENTRATING TABLE.

Application filed May 18, 1921. Serial No. 470,714.

To all whom it may concern:

Be it known that I, CHARLES C. HEBBARD, a citizen of the United States, residing at Joplin, in the county of Jasper and State 5 of Missouri, have invented certain new and useful Improvements in Concentrating Tables, of which the following is a specification, reference being had to the accompanying drawings.

10 This invention relates to concentrating tables, and particularly to the head motions therefor whereby the table is given a longitudinal reciprocating motion.

The general object of this invention is to 15 provide simple and effective means whereby this longitudinal reciprocation of the table can be secured and whereby the table may be jarred by impact with a bumping block, and particularly to provide means 20 whereby the length of the stroke of the table may be adjusted so as to secure a stroke of any desired length up to the maximum radius of the eccentric, and whereby this length of stroke of the table may be at- 25 tained whether there is a light or heavy feed being run on the table, or in other words so construct the table that there will be no increase in the length of stroke with a light feed or any decrease in the length of stroke 30 and of the force of the blow on the bumper if the load is heavy.

A further object is to provide a construction of this character wherein the table is forced forward by means of an eccentric 35 and the bumper block shifted away from the bumper any desired distance, the table and the bumping block being urged forward by means of a spring to cause the forward motion of the table and the impact be- 40 tween the bumping block and the bumper.

And a further object is to provide a mechanism of this character whereby the bumping block carried by the concentrating table may strike the bumper with almost any degree of 45 force desired and at the same time secure a return movement after the impact which is quick at first and then gradually slows up until at the extreme end of the back stroke there is a period of comparative rest which 50 allows the pulp on the deck to settle before the next impact, this variable reciprocating movement combined with the jar given by the impact of the bumping block against the bumper giving the material being treat-

ed a rapid travel on the deck and thus enabling a table operating with this device to treat a much greater quantity of ore than is possible where only a cam or eccentric is used with differential toggles to produce the movement.

Another object is to provide a construction of this character wherein a variable reciprocation of the table is secured by the provision of means permitting the table re- 60 tracting means to move rearward a predetermined distance before exerting any retraction on the deck frame of the concentrator.

And another object is to provide a construction of this character having an ad- 70 justable spring compressed by a movement of the table away from the bumper and which spring, when released, acts to urge the bumping block into contact with the bumper to give the required jar to the table, 75 and provide a second spring whose tension may be so adjusted as either to cause the immediate and full retraction of the table and bumper block from the bumper upon a pre-determined movement of the power oper- 80 ated actuating means or which, when the tension is relaxed, will permit a certain movement of the power operated means before any retraction of the table is effected.

Other objects will appear in the course of 85 the following description.

My invention is illustrated in the accompanying drawings, wherein:—

Figure 1 is a fragmentary top plan view of the head motion of a concentrator, the 90 head motion being partly in section;

Figure 2 is a vertical longitudinal sectional view showing the position of the parts when the table is moved forward to its full extent;

Figure 3 is a like view to Figure 2, showing the position of the parts when the table is retracted and the springs 41 and 58 compressed.

Referring to these drawings, 10 designates 100 the usual frame supporting the concentrating deck, which concentrating deck and frame are of any suitable construction. Adjacent its head end the frame is provided with a relatively heavy transverse beam 11 which, as illustrated, is disposed below the deck of the concentrator and on a level with channel irons 12 which form the beams of

the supporting frame. Attached to these channel irons and thereby connected to the sides of the deck frame are the boxes 13 open at their lower ends and receiving the 5 upper ends of longitudinal yieldable resilient supports 14 illustrated as being formed of rods or strips connected together by a clamp 15 and having their lower ends disposed in a supporting socket 16 on longitudinal sill beams 17. All of these parts are of well known form and form no part 10 of my present invention.

Mounted upon any suitable foundation at the head end of the concentrating table is 15 the bed 18, and mounted in bearings on this bed is the transverse power shaft 19 having a belt wheel 20 whereby power may be applied to the shaft to rotate it. This shaft passes through a casing designed to be filled 20 with oil and designated generally 21 and having a removable cover, and within this casing and mounted upon the shaft for rotation therewith is disposed an eccentric 22. Surrounding this eccentric is an eccentric 25 ring 23 having a yoke 24 extending therefrom, this yoke having a vertically disposed aperture or passage 25 defining a cross bar 26, through which there is an aperture 27. The bed is formed to provide upwardly extending abutments 28 connected at their 30 rear ends by a transverse web 29, the rear face of which is vertical. This web 29 constitutes a bumper and may have cushioning material applied thereto or not as desired.

35 This bumper 29 has a slot 30 through it, through which slot passes the rod 31. This rod at one end passes through a slot 32 formed in the end wall of the casing 21 and the rod is screw-threaded, as at 33, and 40 passes through the aperture 27 in the cross bar 26 of the yoke and is engaged by a nut 34 bearing against the inner face of the cross bar 26. The rod 31 at its end remote from the eccentric is screw-threaded, as at 35, and 45 carries upon it the socket plate 36 which bears against a nut 37 engaging the rod. The intermediate portion of the rod is screw-threaded, as at 38, to engage with a nut 39, and surrounding this portion 38 of the rod 50 is a socket plate 40 confronting the socket plate 36. Disposed between these two plates is the coiled compression spring 41 whose ends engage in sockets in the plates. By turning up the nut 39, it will be obvious 55 that this spring will be compressed toward the plate 36.

The bumper 29 carries upon its ends the rearwardly projecting stud bolts 42, which at one end are screwed into the bumper and 60 which carry the nuts 43. A cross bar 44 which is slotted, as at 45, has perforations at its ends through which the bolts 42 pass, this cross bar bearing against the nuts 43, the rod 31 passing through the slot 45 in 65 this cross bar. Attached to the beam 11 and

projecting therefrom toward the operating eccentric parallel to the rod 31 are the longitudinally extending bolts 46 which have nuts 47 holding the bolts in engagement with the beam 11 and which at their opposite ends are screw-threaded, as at 48, for engagement by pairs of nuts 49 between which is clamped the bumper block 50. This bumper block is vertically slotted, as at 51, for the passage of the rod 31 and may be 75 provided upon its inner face with a cushioning layer, as for instance a layer of rubber 52. This layer of rubber might be mounted either upon the bumper 29 or upon the bumper block 50. The intermediate portions of the bolts 46 are screw-threaded, as at 53, and these portions of the bolts pass loosely through a cross bar 54 held in place upon the bolts by pairs of nuts 55 engaging the screw-threads 53. This cross bar is 80 vertically slotted, as at 56, for the passage of the rod 31. The socket plate 40 bears against one face of this cross bar 54 and a second socket plate 57 bears against the opposite face of the cross bar and confronts 85 the socket plate 44 carried by the bolts 42. Between the socket plate 44 and the socket plate 57 is a coiled compression spring 58. It will be obvious that the pressure of this spring against the cross bar 54 may be increased or diminished by adjusting the nuts 43 and as a consequence adjusting the socket plate 44.

It is obvious that were the deck connected rigidly to the eccentric rod, the deck would 100 travel at the same speed one way as it does the other and that the length of stroke of the table or deck would be equal to the throw of the eccentric, but when this condition is changed and the deck is not so fixed to the eccentric rod but springs are arranged as I have arranged them between the table and the eccentric, it is obvious that the speed of travel of the table can be made unequal in 105 one direction at least and the movement of the table less than the throw of the eccentric. It is not possible for the table to travel at any time faster than the eccentric in either direction, but it can go slower for the reason that the eccentric rod is not rigidly connected to the table but moves it only in one direction, that is rearwardly, and that the table is urged in a forward direction by the spring 58. The eccentric can move faster 110 than the table does, in which case the plate 40 will leave the cross bar 54. It is obvious that the table can be stopped in its forward movement, as by the bumping block, without any stoppage of the eccentric, the rod 31 simply moving onward during the complete 115 throw of the eccentric. Thus, for instance, when there is a very weak tension on the spring 58, the bumping block will barely strike the bumper before the eccentric commences its rearward movement. When, 120

however, there is a very strong tension on the spring 58, the table will move forward as rapidly as the eccentric rod 31 does and will strike the bumper block with great force. Therefore, it is obvious that by adjusting the tension of spring 58, the force of the impact can be adjusted within a relatively large range and that a light or hard impact can be secured by properly tensioning 10 spring 58 which governs the speed of the forward movement of the deck.

Assuming that the springs 41 and 58 have had their tensions initially adjusted to secure the required result and that the spring 15 41 is initially stronger than the spring 58, then as shaft 19 is rotated from the position shown in Figure 1, the eccentric 22 will cause the retraction of rod 31. As rod 31 is drawn rearward, that is away from the deck, 20 it first pulls on spring 41. As this spring 41 is initially tensioned to a greater degree than spring 58, it follows that spring 58 will compress and the draft of the eccentric rod will be communicated to the cross bar 54 25 and that this rearward movement of the cross bar 54 and of the table and of the spring 41 will continue until the spring 58 has been compressed to a degree wherein it is stronger than spring 41. The point at 30 which spring 58 becomes stronger than spring 41 will depend upon the tension initially given to the spring 58. When this point is reached, say at $\frac{3}{4}$ " stroke, the spring 58 becomes stronger than 41 and will stop 35 the rearward movement of the deck and the spring 41 will commence to compress and will continue to be compressed throughout the remaining rearward movement of the eccentric. As the spring 41 compresses, the 40 rod 31 will move rearward and the nut 39 will leave the plate 40, as illustrated in Figure 3.

When the eccentric has made a half revolution and begins its return stroke, the 45 spring 58 will act to return the table to its initial position and cause the bumper block to impact against the bumper with a greater or less degree of force, depending upon the adjustment of the spring 58.

50 It will be obvious that by regulating the tension of spring 58, it may be compressed relatively slightly and then a full stroke of the table will be secured or the tension on the spring may be such that it will hold the 55 table from further rearward movement after the spring 58 has been compressed to a very slight amount and thus a variable stroke is secured which, by adjusting the nut 37, may be controlled and varied so as to secure a 60 stroke of any desired length up to the maximum stroke afforded by the radius of the eccentric. It is to be understood that the 65 springs 41 and 58 are adjusted relatively to each other. Thus, for instance, assume that it is desired to secure a $\frac{3}{4}$ " movement of the

deck, this is secured by adjusting springs 58 and 41 to give the required length of stroke but if it is then found that the bump against the bumping block is not sufficiently hard and the pulp is banking or clogging in the 70 riffles on the deck, more tension is placed on spring 58 so as to secure a greater bumping action. This, of course, shortens the length of the stroke and to adjust it again to a $\frac{3}{4}$ stroke, the nut 37 is turned, making spring 75 41 a little stiffer, as until it is made stiffer the resistance of the spring 41 is not equal to overcoming the added tension put on spring 58. In this manner it is possible to 80 secure either a light or hard bump and at the same time secure any desired length of stroke by relatively adjusting springs 58 and 41.

By the mechanism which I have described, I am enabled to have the bumping 85 block strike the bumper with almost any desired force and at the same time have a return movement which is quick at first and gradually slows up until the extreme end of the back stroke is reached, whereupon there 90 is a period of comparative rest, allowing the pulp on the deck to settle before the next impact. This variable reciprocating movement combined with the jar given by the impact between the bumping block and the 95 bumper gives the material being treated a rapid travel on the deck which enables the table to treat a much greater quantity of ore than is possible on tables operated only by a cam or eccentric combined with the 100 ordinary toggles.

I am aware that it is not new to provide for the slow forward movement of the table and the quick return which acts to pull the deck from under the pulp on its surface, 105 but in addition to this quick return movement of the deck I also secure a bumping action, stopping the deck suddenly by the impact between the bumping block and the bumper. Of course, the pulp which is under momentum will travel much faster on 110 the deck, consequently securing a much greater tonnage of pulp and giving a larger amount of concentrates within a given time than when only a differential movement is 115 employed without a bumper.

While I have illustrated and described an embodiment of my invention which has been found thoroughly effective and which permits the very close adjustment as to stroke, 120 yet I do not wish to be limited to the details of construction nor to the exact arrangement of the parts, as it is obvious that these might be varied in wide limits without departing from the spirit of the invention.

I claim:—

1. In a concentrator, the combination with a deck frame mounted for longitudinal reciprocation, of a fixed bumper, a bumping block reciprocated with and operatively con- 130

- 5 connected to the frame, a spring urging the frame forward and the bumping block against the bumper, power operated means independently movable with relation to but operatively connected to the frame for intermittently retracting it against the force of the spring and releasing the frame to permit it to move forward under the action of the spring and bring the bumper against the 10 bumper block, and adjustable means permitting the retracting means to move rearward a predetermined distance before exerting any retraction on the frame.
- 15 2. In a concentrator, the combination with a deck frame mounted for longitudinal reciprocation, of a fixed bumper, a bumping block reciprocating with and operatively connected to the frame and coacting with the bumper, a spring urging the frame forward and the bumping block against the bumper, power operated means for reciprocating the frame and bumping block including a power operated member independently movable with relation to but reciprocating longitudinally of the deck, a member carried by the deck and toward which the power operated member moves on its rearward stroke, and a member disposed between the power operated member and the second 25 named member and longitudinally adjustable to thereby adjust the instant at which the power operated member will operatively engage to retract the second named member and the deck.
- 30 35 3. In a concentrator, the combination with a deck frame mounted for longitudinal reciprocation, of a fixed bumper, a bumping block reciprocating with and operatively connected to the frame and coacting with the bumper, a spring urging the frame forward and the bumping block against the bumper, power operated means for reciprocating the frame and bumping block including a power operated member movable independently of but reciprocating longitudinally of the deck, a member carried by the deck and toward which the power operated member moves on its rearward movement, and a compression spring disposed between the power operated member and the second 40 45 50 named member.
- 55 60 65 4. In a concentrator, the combination with a deck frame mounted for longitudinal reciprocation, of a fixed bumper, a bumping block reciprocating with and operatively connected to the frame and coacting with the bumper, a spring urging the frame forward and the bumping block against the bumper, power operated means for reciprocating the frame and bumping block including a power operated member reciprocating longitudinally of the deck frame but independently of the deck frame, a member carried by the deck frame and toward which the power operated member moves on its

rearward movement, a compression spring disposed between the power operated member and the second named member, and means for adjustably increasing or decreasing the tension of said spring.

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

and transmitting motion from the reciprocating member to said deck, and means for variably tensioning said spring.

9. A concentrator comprising a deck 5 mounted for reciprocating movement, a longitudinally reciprocatable, power operated member having a constant stroke, a member attached to the deck and forming part thereof and having an opening through 10 which the reciprocatable member freely passes, a fixed bumper, a bumping block carried by the deck and adapted to engage the bumper, a compression spring operatively engaging said second named member 15 and operatively engaged with one end of the reciprocatable member and compressed upon a retraction of the reciprocatable member, a compression spring disposed on the opposite face of said second named member 20 from the first named spring, and a rigid member against which the opposite end of said last named spring engages and adapted to be compressed upon a movement of the deck from the power operated end of the reciprocating member.

10. In a concentrator, the combination with a deck mounted for reciprocating movement and a spring urging the deck in a forward direction, of means for reciprocating 30 the deck including a power operated reciprocating member independent of the deck, a cross bar through which the member loosely passes and which is operatively connected to the deck, a compression spring disposed between said cross bar and that end of the reciprocating member adjacent the deck, the extremity of the reciprocating member having means for operatively engaging the adjacent end of the spring and having means 40 whereby the tension of the spring may be varied.

11. In a concentrator, the combination with a deck mounted for reciprocating movement and a spring urging the deck in a forward direction, of means for reciprocating 45 the deck including a longitudinally extending reciprocating member independently movable with relation to the deck, a cross bar operatively connected to the deck and through which the reciprocating member loosely passes, a member carried on the end of the reciprocating member adjacent the deck, a coiled compression spring disposed between said member and the cross 55 bar, and a nut having screw-threaded engagement with the end of the reciprocating member adjacent the deck and engaging against said last named member whereby to adjustably compress the spring.

60 12. In a concentrator, the combination with a deck mounted for reciprocating movement, of a cross bar operatively connected to the deck, a reciprocating member passing loosely through the cross bar, a compression 65 spring operatively engaging that side of the

cross bar remote from the deck, an abutment against which the end of the spring remote from the deck bears, said abutment being adjustable to increase or decrease the tension of the spring, and a compression spring bearing against that face of the cross bar adjacent the deck and operatively engaged with that end of the reciprocating member adjacent the deck.

70 13. In a concentrator, the combination 75 with a deck mounted for reciprocating movement, of a cross bar operatively connected to the deck, a reciprocating member passing loosely through the cross bar, a compression spring operatively engaging that side of the cross bar remote from the deck, an abutment against which the end of the spring remote from the deck bears, said abutment being adjustable to increase or decrease the tension of the spring, a compression spring bearing against that face of the cross bar adjacent the deck and operatively engaged with that end of the reciprocating member adjacent the deck, and a nut carried on the extremity of the reciprocating member and 80 operatively engaging said spring whereby it may be variably compressed.

85 14. In a concentrator, a deck mounted 95 for reciprocating movement, a pair of rods operatively connected to the deck and extending rearward therefrom, a cross bar carried upon said rods and moving therewith, a power operated reciprocating member passing loosely through the cross bar, a compression spring operating against one side 100 of the cross bar to urge it in one direction and resist its movement in the opposite direction, and a compression spring disposed between the reciprocating member and the other face of said cross bar.

105 15. In a concentrator, a deck mounted for reciprocating movement, a pair of rods extended from the deck, a cross bar mounted upon said rods and moving therewith, a power operated reciprocating element passing loosely through the cross bar, a coiled compression spring bearing against the rear face of the cross bar, adjustable means supporting the other end of the spring whereby 110 said spring resists the rearward movement of the cross bar and the concentrating table, a coiled compression spring bearing against the opposite face of the cross bar, and means on the extremity of the reciprocating element engaging that end of said spring adjacent the deck, said means being adjustable 115 to adjust the tension of the spring.

16. A concentrator having a deck mounted 120 for reciprocating movement, a pair of rods extending from the deck, a bumping block carried upon said rods for movement therewith, a rigid bumper against which the bumping block is adapted to impact, a cross bar mounted upon said rods for movement therewith and disposed between the bump- 125

ing block and the deck, a power operated reciprocating element passing loosely through the bumping block, the bumper and the cross bar, a coiled compression spring bearing against the rear face of the cross bar and urging the deck in a forward direction, means carried by the bumper supporting the rear end of the compression spring, and a compression spring bearing against the forward face of the cross bar, the forward end of said compression spring operatively engaging the forward end of the reciprocating element.

17. A concentrator having a deck mounted for reciprocating movement, a pair of rods extending from the deck, a bumping block carried upon said rods for movement therewith, a rigid bumper against which the bumping block is adapted to impact, a cross bar mounted upon said rods for movement therewith and disposed between the bumping block and the deck, a power operated reciprocating element passing loosely through the bumping block, the bumper and the cross bar, a coiled compression spring bearing against the rear face of the cross bar and urging the deck in a forward direction, a seat for the other end of the spring adjustably mounted upon the bumper for adjustment toward or from the cross bar to thereby variably tension said spring, a power operated reciprocating element passing through the bumping block, the bumper and said cross bar, a nut carried upon that end of the reciprocating element adjacent the deck, and a coiled compression spring disposed between said nut and that face of the cross bar adjacent the deck and operatively engaged by the nut whereby the last named spring may be variably tensioned.

18. A concentrator comprising a reciprocatable deck, means for reciprocating the deck including a reciprocatable, longitudinally extending rod independently movable with relation to the deck, a member carried by the deck and through which said rod loosely passes, a compression spring disposed between one face of said member and the inner end of said rod, a nut mounted on the rod adjacent the said member whereby the spring may be compressed and shifted out of engagement with the member, a second compression spring having one end disposed against the opposite face of the said member, and an abutment against which the other end of the second named spring bears, said abutment being adjustable to thereby control the tension of the spring.

19. A concentrator comprising a reciprocatably mounted deck, a longitudinally reciprocatable operating rod movable independently of the deck, a member attached to the deck and forming part thereof and through which said rod loosely passes, a

plate loosely mounted upon the rod and adapted to bear against one face of said member, a nut on the rod adapted to urge the plate toward the inner extremity of the reciprocating rod, a spring support on the inner end of the rod, a coiled compression spring disposed between said plate and the spring support, a second spring operatively engaging the opposite face of said member, and an adjustable abutment against which the opposite end of said last named spring bears.

20. In a concentrating table, a deck, a bumper, a bumping block operatively carried by the deck and coacting with the bumper, means urging the deck and bumping block toward the bumper, and power operated means retracting the bumping block and deck quickly during the initial movement of the bumping block away from the bumper and then slowly, but permitting the bumping block and deck to move forward quickly to bring the bumping block into contact with the bumper whereby to secure a period of rest at the time when the deck is fully retracted to thereby allow the pulp on the deck to settle before the next impact.

21. In a concentrator, the combination with a deck frame mounted for longitudinal reciprocation, of means urging the deck frame in one direction and power operated means operatively connected to the frame for intermittently retracting it against the urging means, and adjustable means permitting the retracting means to move rearward a predetermined distance before exerting any retraction on the frame.

22. In a concentrator, a longitudinally shiftable concentrating table, a reciprocatable rod associated therewith for reciprocating the same but independently movable with relation to the table, resilient means yieldably connecting the rod to the table and adjustable as to tension, and means resisting the movement of the deck after it has moved a predetermined distance under the action of said reciprocating means and the resilient means.

23. In a concentrator, a longitudinally movable deck, a bumper moving therewith, a fixed bumping block, a reciprocating power operated rod, a member carried by the deck and through which the rod passes, compression springs disposed on either side of said member, to one of which springs the reciprocating rod is connected, the other spring being supported by a relatively fixed abutment, and means for varying the tension of said springs relative to each other.

In testimony whereof I hereunto affix my signature.

CHARLES C. HEBBARD.
